UNITED STATES PATENT OFFICE

98,174

DESIGN FOR A CANDLESTICK

William F. Liska, Chicago, Ill., assignor to Holland Brass Works, Incorporated, Chicago, Ill., a corporation of Illinois

Application April 4, 1935, Serial No. 56,201

Term of patent 3½ years

To all whom it may concern:

Be it known that I, William F. Liska, a citizen of the United States, residing at Chicago, in the county of Cook and State of Illinois, have invented a new, original, and ornamental Design for a Candlestick, of which the following is a specification, reference being had to the accompanying drawing, forming a part thereof.

Referring to the drawing, Fig. 1 is a front view and Fig. 2 is a side view of a candlestick, showing my new design.

I claim:

The ornamental design for a candlestick, as shown.

WILLIAM F. LISKA.
